(57) **CLAIM**

The ornamental design for a lamp for manicure, as shown and described.

DESCRIPTION

FIG. 1 is a front, right and top perspective view of a lamp for manicure, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front, left and top perspective view thereof;

FIG. 10 is a front, right and top perspective view in open status thereof; and,

FIG. 11 is a front, left and top perspective view in open status thereof.

The broken lines shown in the drawings illustrate portions of the lamp for manicure that form no part of the claimed design.
